(57) **CLAIM**

The ornamental design for a plug device as shown and described herein.

DESCRIPTION

FIG. 1 is a first perspective view of a plug device according to our new design;

FIG. 2 is a second perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in FIGS. 1 and 7 depict portions of the plug device that form no part of the claimed design.

1 Claim, 6 Drawing Sheets
